UNITED STATES PATENT OFFICE.

ROBERT GOLDE, OF BROOKLYN, NEW YORK, ASSIGNOR TO THE ROYAL
METAL MANUFACTURING COMPANY, OF NEW YORK.

DESIGN FOR A PICTURE-FRAME.

SPECIFICATION forming part of Design No. 23,184, dated April 10, 1894.

Application filed February 13, 1894. Serial No. 499,997. Term of patent 3½ years.

To all whom it may concern:

Be it known that I, ROBERT GOLDE, a subject of the Emperor of Germany, residing at Brooklyn, in the county of Kings, State of New York, have invented and produced a new and original Design for a Picture-Frame, of which the following is a specification, reference being had to the accompanying drawing, forming part thereof.

- o The leading features of my design for a picture frame, are first the sides of the same representing roses, buds and leaves, the stems of which extend in serpentine direction, and next an inner border of rustic form.
- 5 In the drawing: A designates a frame, the

sides of which are formed of the representations of roses B, buds C, leaves D, and stems E, the stems passing the roses in serpentine form.

F designates the inner border of the picture frame, the same being of rustic form and joining the roses, buds, stems and leaves.

What I claim is—

The design for a picture frame substantially as shown and described.

ROBERT GOLDE.
